Specification for Design.

Patented Nov. 6, 1917.

Application filed July 30, 1917. Serial No. 183,623. Term of patent 14 years.

To all whom it may concern:

Be it known that I, CHARLES S. ANDREWS, a citizen of the United States, residing at Boston, in the county of Suffolk and Commonwealth of Massachusetts, have invented a new, original, and ornamental Design for Cabinets, of which the following is a specification, reference being had to the accompanying drawing, forming part thereof, in which—

Figure 1 represents a perspective view of a cabinet showing the front and one side of my new design, and,

Fig. 2 represents a perspective view of the same showing the front and the other side of the cabinet.

I claim:

The ornamental design for a cabinet, as shown.

CHARLES S. ANDREWS.
